(57) **CLAIM**

The ornamental design for a medical marking pen as shown and described.

DESCRIPTION

1. Medical marking pen
- 1.1: Perspective view (front, top and left)
- 1.2: Perspective view (front, bottom and right)
- 1.3: Front
- 1.4: Left
- 1.5: Right
- 1.6: Top
- 1.7: Bottom
- 1.8: Cross sectional
- 1.9: Cross sectional
- 1.10: Exploded
- 1.11: Enlarged
- 1.12: Enlarged

Design 1: The article is a medical marking pen mainly used to mark skin, bones, etc. in surgical procedures or animal experiments; the feature of the design resides in shape and configuration of the article as shown in the reproductions; the back view is omitted since it is a mirror image of front view; reproduction 1.8 is an cross-sectional view taken along line A-A in reproduction 1.3; reproduction 1.9 is a cross-sectional view taken along line B-B in reproduction

(Continued)

1.6; reproduction 1.10 is an exploded perspective view showing the removal of a cap configuring the medical marking pen; reproduction 1.11 is a reference partial enlarged front view taken along the line C-C in reproduction 1.3, wherein the oblique surface shading depicts a transparent part; reproduction 1.12 is a reference partial enlarged perspective view taken along the line C-C in reproduction 1.3.
